SHREDDING MACHINE

Arthur H. Menkin, Elmhurst, and Charles H. Morhardt, Baldwin, N. Y., assignors to The Shredmaster Corporation, a corporation of Delaware

Application August 6, 1948, Serial No. 42,774

5 Claims. (Cl. 164—60)

1

This invention relates to shredding machines more particularly of the type adapted to cut paper or other material into narrow strips.

It is among the objects of the invention to provide a machine of the above type that is neat in appearance, durable, relatively compact, easy to assemble and relatively noiseless in operation, that functions with a minimum of supervision requiring the operator only to feed material thereto and remove the collected shredded material, that it not likely to clog or jam during the operation thereof but in the remote event of clogging or jamming may readily be cleared, that functions with a minimum of vibration, the speed of which may readily be changed without need for special tools, that is designed to prevent injury to the operator having but a minimum of exposed parts and that may readily be disassembled for maintenance or service.

Another object of the invention is to provide a machine of the above type which may be used for slippery material such as waxed paper and ensures positive movement of such material through the machine.

Another object is to provide a machine of the above type wherein the material to be cut may automatically be fed into the machine.

Another object is to provide a machine of the above type wherein letters and other documents may readily be cut into small segments.

According to the invention these objects are accomplished by the arrangement and combination of elements hereinafter described and particularly recited in the claims.

In the following drawings in which is shown one or more of various possible embodiments of the several features of the invention,

Fig. 1 is a perspective view of the machine,

Fig. 2 is a transverse sectional view taken along the line 2—2 of Fig. 1,

Fig. 3 is a front elevation of the machine with parts broken away,

Fig. 4 is a transverse sectional view on a larger scale taken along line 4—4 of Fig. 3,

Fig. 5 is a longitudinal sectional view taken along line 5—5 of Fig. 4,

Fig. 6 is a fragmentary plan view on a smaller scale taken along line 6—6 of Fig. 5,

Fig. 7 is a sectional view on a larger scale taken along line 7—7 of Fig. 6,

Fig. 8 is an exploded perspective view showing the cutting blades, the strippers or combers and the spacing members,

Fig. 9 is a sectional view on a larger scale taken along line 9—9 of Fig. 2,

2

Fig. 10 is a fragmentary view of another embodiment of the invention,

Fig. 11 is a fragmentary perspective view of still another embodiment of the invention,

Fig. 12 is a plan view of another embodiment of the cutting blade, and

Fig. 13 is a view similar to Fig. 12 of still another embodiment of the cutting blade.

Referring now to the drawings, the machine 10 comprises a substantially U-shaped frame 21 preferably of cast iron, the legs 22 thereof each having a transverse flange 23 at the lower end thereof extending laterally outward therefrom, said flanges 23 mounting casters 23' whereby 15 the machine may readily be moved. In order to prevent the legs 22 from spreading, angle irons 25 and 26 are provided extending longitudinally of the frame and affixed at each end respectively by screws 24, to transverse flanges 30 extending laterally inward from the lower ends of legs 22 and preferably integral therewith.

The cross piece of the frame which forms a table portion 27 near the mid portion thereof, has a depending skirt 28 on the front edge thereof, 25 preferably formed integrally therewith and which extends the entire length of the cross piece. The rear edge of table portion 27 has a depending portion preferably integral therewith forming a chute 29 which is substantially the same width as table portion 27 and slopes rearwardly as shown in Fig. 2.

Each end of the cross piece adjacent table portion 27 forms a bed or base 31 and 32 respectively, substantially the width of the legs 22, 35 base 31 being at a lower level than table portion 27 and base 32, as shown in Fig. 5. Base 31 has a longitudinal slot 33 (Figs. 3, 4) therethrough, adjacent skirt 28 for the drive transmission to be hereinafter described.

40 Mounted on bed 31 and extending upwardly therefrom is a gear box 34 rigidly affixed to bed 31 by screws 35 extending through flange 40 at the lower edge of the gear box 34 and preferably integral therewith. The gear box 34 has a

45 removable cover plate 36 affixed on the top thereof by screws 37, a threaded plug 38 being provided in said cover plate 36 to close the lubricant inlet. Drain plugs 39 are provided in the bottom of the gear box 34, the bed 31 having an

50 aperture 41 therein to permit ready access to said plugs 39 to drain the oil from the gear box 34. Desirably a test plug 40 is provided threaded in an opening in side wall 41 of the gear box

55 at a height above the bottom of the gear box below which the level of the lubricant therein

should not fall. Thus if with the test plug 100 removed no lubricant flows from the opening, the gear box should be recharged with lubricant.

The front and rear walls 43 and 44 respectively of the gear box 34, near the bottom thereof, have transversely aligned recesses 45 and 46 therein, with apertures 47 and 48 respectively therethrough. Extending through said apertures is a worm shaft 51, journalled in ball bearings 52 and 53 near its front and rear ends respectively. Bearings 52 and 53 are seated in recesses 45 and 46 against the inturned rims 55 and 56 thereof respectively. In order to prevent axial movement of shaft 51 in its bearings and retain the bearings in their respective recesses, the shaft 51 is threaded as at 57 and 58 and nuts 59 and 61 are affixed respectively on said threaded portions.

To prevent entry of dirt and dust into the bearings 52 and 53 and prevent leakage of oil from the gear box 34, a cover plate 64 is affixed to the rear wall 44 of the gear box over bearing 53 by screws 65 and a similar cover plate 67 is affixed to the front wall 43 of the gear box 34 over bearing 52 by screws 68, the last named cover plate having an oil seal or packing 72 around opening 69 to prevent leakage of oil through aperture 69 through which the front end 71 of the worm shaft 51 protrudes.

Affixed to the front end 71 of worm shaft 51 over slot 33 in base 31 are a plurality of pulleys of different diameters two being illustratively shown designated by the numerals 74 and 75. In order to rotate the pulleys 74 and 75 and drive worm shaft 51, a motor M is provided positioned beneath the gear box 34 and affixed by bolts 77 to a substantially rectangular base or platform 78. Platform 78 has a pair of aligned depending ears 79 on each side thereof through which a transverse pivot rod 81 extends, rigidly affixed at each end in angle irons 25 and 26 pivotally to mount platform 78. In order to limit the pivotal movement of platform 78, a transverse rod 82 is provided rigidly mounted in angle irons 25 and 26 near the free end of platform 78. An eye bolt 84 is pivoted on rod 82 and has its threaded end 83 extending through an opening in platform 78, a pair of nuts 85 being provided screwed on the threaded end of eye bolt 84 against each face of platform 78 rigidly to clamp the latter therebetween.

The drive shaft 86 of motor M has a plurality of pulleys P thereon, illustratively two in number of different diameter, the smaller pulley on shaft 86 being aligned with the larger pulley 74 on shaft 51 and the larger pulley on shaft 86 being aligned with the smaller pulley 75 on shaft 51. It is thus apparent that by placing the belt 97 on different pairs of aligned pulleys, either of two speeds may be selected. It is of course to be understood that a greater number of pulleys could be provided on shafts 86 and 51 to provide for a greater range of speeds. In order that a single size belt can be used for different speeds, the aligned pairs of pulleys are of such diameter that the length of the belt around each of the aligned pairs of pulleys will be the same.

Positioned on base 32 and extending transversely thereacross as shown in Figs. 5, 6 and 7 is a substantially L-shaped tail-stock 91. The base 92 of the tail-stock has a pair of longitudinally aligned slots 93 and 94 therethrough on each side thereof through each of which extends a screw 95 threaded into an associated opening 96 in base 32, the slots permitting longi-

tudinal adjustment of the tail-stock when the screws 95 are loosened. In order to facilitate such adjustment, a pair of handles 97 are provided preferably integral therewith on opposite sides thereof.

Extending laterally outward from the upright portion 98 of the tail-stock 91 are a pair of hubs 99 and 101, the latter being positioned below the former and forwardly thereof as shown in Fig. 10 6. The hubs 99 and 101 have openings 103 and 104 therethrough respectively, aligned with corresponding openings 105, 106 and 107, 108 in the side walls 109 and 111 respectively of the gear box 34.

15 A pair of shafts 112 and 113 are provided positioned longitudinally of the frame 21 and extending through openings 103, 105 and 107 and 104, 106 and 108 respectively. As the construction and mounting of said shafts 112 and 113 are substantially identical only the former, i. e. shaft 112 will be described in detail, corresponding parts of the latter having the same reference numerals primed.

20 Shaft 112 has a reduced portion 115 adjacent side wall 109 of the gear box 34 around which a ball bearing 116 is positioned, the latter being seated against the inturned flange 117 of opening 105.

25 Shaft 112 has an encompassing collar 119 adjacent bearing 116 with a notch therein whereby the collar may be keyed to shaft 112 in the manner hereinafter described so that collar 119 will rotate with shaft 112.

30 Shaft 112 and collar 119 and seated in a recess 122 in side wall 109, said seal ring being retained in said recess by screws 123. As shown in Fig. 5 the inner face 124 of collar 119 extends slightly beyond the face of seal ring 121. The seal ring has an annular washer 125 preferably of felt, on the inner edge thereof, which abuts against collar 119 to prevent leakage of oil from the gear box and reduce the friction between the collar and seal ring.

35 The end of shaft 112 is journalled in a ball bearing 126, the latter encompassing the reduced portion 127 of the shaft and seated against shoulder 128 formed by said reduced portion. The bearing 126 which is positioned in opening 107 in side wall 111 of the gear box 34 is retained on shaft 112 by means of a nut 129 threaded on the end 131 of the shaft 112.

40 Keyed on the portion of shafts 112 and 113 in the gear box are meshed spur gears 132 and 133 respectively which are spaced from bearing 116 and 116' by means of sleeves 134 and 134' respectively.

45 By means of a nut 135 screwed on the threaded portion 136 of shaft 112, spur gear 132, sleeve 134, bearing 116 and collar 119 are retained against axial displacement on shaft 112.

Also keyed in shaft 113 is a worm gear 137 spaced by sleeve 138 from spur gear 133 and by sleeve 141 from bearing 126' positioned in opening 108 in side wall 111 of the gear box. A nut 129' screwed on the threaded end 131' of shaft 113 prevents axial displacement of bearing 126', sleeve 141, worm gear 137, sleeve 138, spur gear 133, sleeve 134', bearing 116' and collar 119'.

50 The worm gear 137 meshes with a worm 144 keyed on worm shaft 51 to drive shafts 112 and 113 when the worm shaft is rotated in the manner hereinafter described.

55 In order to prevent the entry of dirt and dust

into the gear box and also to prevent the leakage of oil therefrom, cover plates 147 and 147' are provided affixed to the gear box over the ends 131 and 131' of shaft 112 and 113 respectively by screws 148.

Mounted on shafts 112 and 113 between end wall 109 of the gear box and upright portion 99 of the tail stock are a series of opposed circular cutting knives 151 and 152 respectively which are secured to their respective actuating shaft in any desired manner, keys 153 and 154 being preferably used, positioned in the keyways 155 and 156 respectively in the shafts and engaging corresponding notches 157 in the knives as well as corresponding notches in the associated collar 119, 119'. A series of spacer collars 158 and 159 each having a notch 161 is similarly mounted on each shaft between consecutive cutters, and each series of knives is so located with reference to the other as to be positioned opposite to the spacer collars of the opposing series with the cutting edges thereof overlapping.

The cutting knife cleaning devices or combers 162 and 163 in this mechanism which are mounted in like plurality between the knives 151 and 152 of each series, each takes the form of a substantially circular plate having an opening 160' therethrough of greater diameter than that of the associated spacer 158 or 159 and preferably encompassing said spacers respectively. As the thickness of the spacers is slightly greater than that of the combers, the latter will ride between the faces of the cutting knives with but a minimum of friction.

Suitably formed extension 164 and 165 are provided on the combers 162 and 163 respectively, preferably integral therewith and lying in the same plane therewith, each of said extensions having a substantially rectangular opening 167 therein through which the supporting bars 198 and 169 respectively extend.

Bar 168 is affixed at one end by means of a screw 171 to the top of the gear box 34 and extends longitudinally of the shaft 112 to the tail-stock 91. The other end of bar 168 has a longitudinal slot 172 therein through which a screw 173 extends threaded into an opening 174 in the top of the upright wall 98 of the tail-stock. Thus bar 168 supports members 167 with the extensions 164 thereof in a substantially upright position.

Bar 169 is affixed at one end by screw 175 to the front wall of the gear box and extends longitudinally of the shaft 113 to the tail stock 91. The other end of bar 169 also has a longitudinal slot 176 therein through which a screw 177 extends threaded into an opening in hub 101 of the tail stock as shown in Fig. 6. Thus bar 169 supports members 163 with the extensions 165 thereof at substantially right angles to extensions 164.

As shown in Fig. 2 the combers are so formed that at the points indicated by the numerals 178 and 179 the opposed and adjacent edge portions thereof lie within the peripheral edges of the knives between which they are positioned. From this point the edge portions are carried gradually outward to the points 181 and 182 where they overlap the peripheral edges of the knives.

Thus as the material is fed to the machine and cut, the strips which adhere between the cutting edges of the knives are carried thereby from the point indicated by the numeral 183 to the point where they encounter the overlapping edge portions 181 and 182 of the combers. 162

and 163 respectively and are forced out from between the cutting edges of the knives.

The positioning of the knife, spacer and comber elements may readily be seen in Figs. 5 and 8, the elements shown in Fig. 5 being exaggerated in thickness to facilitate a clear understanding of the machine.

In a preferred embodiment of the invention the machine is set up with elements $\frac{3}{2}$ inch in width. 10 If it is desired to shred up to $\frac{3}{2}$ inch, knives, combers and spacers are set up on the shaft singly as shown. If it is desired to shred $\frac{1}{8}$ inch strips, the individual elements are placed on the shaft two at a time. If $\frac{3}{2}$ inch widths 15 are desired, the elements are placed on the shafts three at a time and so on. This change of width may readily be accomplished by the user as desired.

Encompassing the reduced portions 191, 191' 20 of shafts 112 and 113 respectively and seated against shoulders 192 formed by said reduced portions are ball bearings 193, 193' respectively of diameter substantially the same as the opening 163, 164 in hubs 99 and 101 respectively so as to permit axial movement of the shafts 112 and 113 and their respective bearings 193 and 193' in the manner hereinafter described but preventing lateral movement thereof. Bearings 193 and 193' are retained against their associated shoulders 192 by sleeves 194 encompassing the end portion 195 of the respective shafts and retained therein each by a nut 196.

Shafts 112 and 113 each has an encompassing collar 197 with a notch 198 therein through which keys 153 and 154 respectively extends thereby affixing the collars to their respective shafts to rotate therewith, yet permitting the collars to be moved axially thereon. Abutting against each of the collars 197 respectively is a nut 199 35 screwed on the threaded portion 201 of the shaft adjacent collars 197 and by means of which the axial position of the collars may be determined.

Seal rings 202 and 202' are also provided, 40 encompassing shafts 112 and 113 and their associated collars 197 respectively and seated in recesses 203 and 203' respectively in the inner face of upright portion 98, and retained in said recesses by screws 204. Each of the seal rings has an annular washer 205 preferably of felt on the inner edge thereof which engages collar 197 to reduce the friction between the seal ring and collar.

To prevent injury to the operator and also to prevent the entry of dirt and dust as well as the shredded material into the machine, which might cause jamming of the latter, suitable coverings are provided.

As shown in Figs. 1, and 3, the skirt 28 and legs 22 of the frame have a flange 211 to which a sheet metal cover 212 is affixed by screws 213. 55 In order to provide access to the motor M and pulleys thereon, a door 214 is hingedly mounted on the sheet metal cover 212 as at 215. A sheet metal housing 216 is provided for the gear box 34, which is affixed to bed 31 and is provided with a door 217 hinged to the front wall 218 of the housing 216 as at 219 to provide access to pulleys 74 and 75. A sheet metal housing 221 60 is also provided for the tail-stock 91 and is affixed to bed 32 as shown in Fig. 5.

Extending longitudinally of the machine over the portion of shafts 112 and 113 on which the knives are mounted is a sheet metal reflector 222 affixed at each end to housing 216 and 221 65 respectively and provided with illuminating

means such as bulbs 225 to cast light on the cutting portion of the machine.

To facilitate feeding material into the machine, a table 226 is provided. As shown in Figs. 2 and 3 the table has a substantially L-shaped bracket 227 affixed theretophere along each side edge thereof. As shown in Fig. 2 the vertical leg 228 of the bracket has an elongated slot 229 therein and a finger 231 extending longitudinally thereof having a notch 232 therein. A pair of spaced studs 233 and 234 are provided on each of the opposing walls 109 and 98 of the gear box and tail-stock respectively, extending laterally outward therefrom. Studs 233 extending through the longitudinal slot 229 of the associated brackets 227 pivotally to mount the table, the latter being retained in a horizontal position by seating studs 234 in notches 232 of fingers 231 as shown in full lines in Fig. 2.

The table 226 has an inclined lip 247 rigidly affixed to its rear edge 248 to facilitate feeding the machine when the table is in horizontal position.

In order to safeguard the operator as he feeds the machine, a pivoted shield 249 is provided comprising a horizontal portion 251 substantially the width of the table 226, having an upturned front edge 252 to which a knob 253 is affixed and a downwardly inclined rear portion 254 substantially parallel to inclined lip 247 of table 226 as shown in Fig. 2.

Rigid with portion 251 and extending obliquely upward therefrom is a plate 255 having a window 256 therein preferably of plastic or other transparent shatterproof material. The upper edge of plate 255 has a rearwardly extending flange 257 preferably integral therewith, at each end of which is affixed a stud 258 extending longitudinally of the plate 255.

A pair of L-shaped brackets 259 are affixed respectively on the top of the housings 216 and 221, the upstanding leg of said brackets each having a notch 261 therein in which studs 258 may respectively be positioned pivotally to support the shield 249. In order to limit the pivotal movement of shield 249, a bracket 263 is affixed at each edge of horizontal portion 251, the laterally extending arms 264 of the bracket resting on the top of housings 216 and 221 respectively when the shield is in closed position.

Associated with one of said brackets 263 is an electrical switch 266 mounted in housing 216. The lateral extending arm 264 of bracket 263 contracts the operating plunger 267 of the switch when the shield is in closed position to close the switch, the latter automatically opening when arm 264 is moved away from plunger 267 by the pivoting of shield 249.

An upright shield plate 271 is also provided affixed beneath table 226 to bed portion 27 as shown in Figs. 1 and 2 to prevent the operator from touching the cutting knives when the machine is in operation and also to prevent backing up of the shredded material when the machine is functioning.

Affixed on the table 226 on each side thereof near the free end of the table, is an adjustable paper guide, preferably comprising two L-shaped members 236 and 237, the vertical legs 238 and 239 of which are clamped together by a wing nut and bolt 241, the latter extending through a vertical slot 242 in leg 239 to permit vertical adjustment of the laterally extending leg 243 of the guide. The foot 244 of the guide is secured to the table 226 by wing nut and bolt 245, the

latter extending through a slot 246 in said foot to permit lateral adjustment of the guide on the table.

In order to energize motor M, a switch box 272 is provided, mounted on a bracket 273 affixed to skirt 28 of the frame. The switch box is connected by a lead 275 to control box 276 mounted on leg 22 of the frame as shown in Fig. 2.

The switch box preferably has three buttons, i. e. start, stop and reverse, the latter button requiring constant pressure thereon for actuation thereof. As the circuit and control elements for the switch box which are contained in the control box are conventional, they will not be further described.

Adjustment and operation

With the machine assembled as heretofore described, nuts 135 and 199 on shaft 112 and nuts 129' and 199' on shaft 113 are tightened to compress the knives and spacers therebetween so that they are rigidly retained on their respective shafts. As combers 162 and 163 are positioned between the knives, encompassing their associated spacers which are thicker than the combers, the combers will ride between the knives with but a minimum of friction. As comber 162 on shaft 112 and knives 152 on shaft 113, on the left side of the machine as seen in Fig. 5, adjacent the seal rings 121, and 121' respectively of gear box 34 are spaced therefrom by reason of the slight protrusion of collars 119 and 119' beyond the inner face of the seal rings, there will be no contact between the knife and comber and their respective seal rings and hence no friction therebetween. This space is so small that there is little likelihood of the shredded material jamming therein which would interfere with the operation of the machine.

As the tail-stock 91 is movable longitudinally of the frame, accurate tolerances in the construction of the machine is not required to ensure that the space between seal rings 202 and 202', and the comber and knife adjacent thereto respectively, will be as small as possible to prevent collection of the shredded material therebetween. It is merely necessary for the operator to loosen screws 95 and move the tail-stock to the desired position and thereupon tighten screws 95 to retain the tail-stock in place.

To operate the machine the operator need merely press the start button shown in Fig. 1 to cause the shafts 112 and 113 to rotate in opposite directions as shown in Fig. 2, shaft 112 rotating in a clockwise direction and shaft 113 rotating in a counterclockwise direction. As the window 256 in the shield 249 affords a clear view of the illuminated knives, the operator may readily feed material thereto by placing the same on table 226 and moving it beneath shield 249 through the slot formed by inclined portion 254 thereof and lip 247, so that it is caught by the rotating knives which will pull the material therebetween and cut the same into strips, the latter thereupon dropping down on chute 29 to slide out of the machine. To prevent accumulation of the strips beneath the machine when casters are used, a pivoted plate 280 is desirably provided which is aligned with chute 29 to direct the strips away from the machine. This is clearly shown in Fig. 2.

If paper is to be shredded that is of greater width than the cutting portion of the machine, the adjustable paper guides will cause the paper

to be curled over as it is fed into the machine thereby preventing such paper from getting caught in the spaces adjacent the seal rings and possibly jamming the machine.

If the machine should jam, it is merely necessary for the operator to press the stop button, then momentarily press the reverse button which will reject the material between the blades. The material may then be properly positioned in the machine and the start button again pressed.

In the eventuality that the reverse rotation should fail to clear the machine and the operator should desire manually to pull the material jammed between the knives, in order to reach the knives, he must first lift the shield 249. This will remove bracket arm 234 from safety switch plunger arm 267 and stop the machine thereby preventing any possibility of injury.

If the operator should desire to change the speed of the machine, he need merely press the stop button, open doors 214 and 217 and switch the belt 87 to the desired size pulleys. To facilitate such adjustment, the nuts 85 on eye bolt 84 are first loosened and the platform pivoted upwardly to slacken the belt 87. With the belt on the proper pulleys, the weight of the motor on the platform will keep the belt taut and the nuts 85 may then be tightened to retain the platform in place.

With the construction herein described when material is inserted between the knives, any tendency of the shafts 112 and 113 to bow materially is prevented by reason of the double bearing support therefor in the gear box 34. If not for such dual support, the bowing might move the ends 131 and 131' of the shafts out of line resulting in severe vibration which would cause considerable noise and tend to loosen the operating parts of the machine resulting in breakdown of the latter, thus requiring constant maintenance thereof.

When it is desired to cut slippery material such as waxed paper which might not readily be caught by the smooth periphery of circular knives and pulled therethrough, the cutting knife 282 as shown in Fig. 12 or the knives 283 shown in Fig. 13 could be used. Knife 282 has a small notch 284 in the periphery thereof which would catch on the paper and pull it through and the flats 285 on knives 283 would also serve the same purpose.

In Fig. 10 an embodiment of the machine is shown which is especially designed to cut confidential documents such as letters or other papers into small pieces. As shown in the drawing two parallel shafts 287 and 288 are provided lying in the same horizontal planes with a plurality of knives 289, spacers 290 and combers 291 on each shaft. As the construction and assembly of such machine is substantially similar to the one shown in Figs. 1 to 9, it will not be described in detail.

It is to be noted that substantially the entire periphery of the combers 291 lie within the periphery of the knives 289 and only near the top of the knives as at 292 does the sloping edge 293 of the combers extend beyond the periphery thereof.

A hopper 294 is provided with the outlet 295 thereof positioned directly over the overlapping portion 300 the knives and deflectors 296 are provided at the outlet 295 extending laterally outward and downwardly so as to extend beyond the knives.

When the paper is dropped into the hopper it will fall between the knives and initially be shredded into strips. The strips will stick in the

space between the knives and be carried around until they abut against the sloping edge 293 of the combers 291 to be forced out of the space between the knives. As the strips are forced outwardly, they will abut against the deflector 296 as at 297 and curl over the top of the combers as at 298 to again pass between the cutting edges of the knives. As the strips will now not be aligned with the spaces between the knives but 10 will be at an angle thereto, they will again be cut, but this time into smaller segments, the smaller of which will not stick between the knives but will fall downwardly. The larger segments which remain between the knives will again be forced 15 outwardly by the combers and be deflected over the top thereof to again fall between the knives whereupon they will again be cut into still smaller segments. This procedure will be repeated until all the paper has been cut into very small segments which will be discharged from the machine, which segments would be almost impossible to piece together and read.

The small segments may be collected in a basket (not shown) positioned below the overlapping 25 edges 300 of the knives to be subsequently burned.

In Fig. 11, the machine shown in Figs. 1 to 9 has been slightly modified so that a conveyer system may readily be incorporated therewith.

To this end a plurality of cutting knives 301, 30 combers 302 and spacers 303 are positioned on shafts 304 and 305 in the manner heretofore described, illustratively in sets of four instead of the individual elements shown in Figs. 1 to 9. Alternate sets of combers 302 on the lower shaft 35 305 are replaced by pulleys 306 which latter are keyed to shaft 305 by key 307. It is of course to be understood that all of the sets of combers 302 on the shaft 305 could be replaced by pulleys 306 or some intermediate arrangement could be 40 used.

The pulleys 306 each have a continuous belt 303 therearound which encircles an idler pulley 309 mounted on a shaft 311, the belt being normally retained in taut condition in a horizontal 45 position.

To operate the machine shown in Fig. 11, the operator need merely place the material to be shredded on the belts 308 which will carry such material to the overlapping portion of the cutting knives, whereupon it will be drawn therethrough. As the strips of material between the cutting knives encounters the combers 302 on shafts 304 and 305, the combers will force the strips outwardly from between the knives so that 55 it may be discharged from the machine. In the case of the strips in the spaces between the knives occupied by the pulleys, the strips will abut against the belts and be forced outwardly from between the knives in the same manner as if 60 the combers had been used.

Thus by the above construction, the shredding machine may readily be supplied with a conveyer belt with resultant convenience in feeding the machine and increase in the output therefrom 65 and this advantage may be secured without any material modification in the design of the machine.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described our invention what we claim as new and desire to secure by Letters Patent of the United States is:

1. A shredding machine comprising a pair of parallel rotary shafts, a series of spaced circular cutting knives assembled on each of said shafts and rigidly affixed thereon to rotate therewith the cutting knives on one of said shafts alternating with and overlapping the cutting knives on the other of said shafts, a series of stationary combers on each of said shafts between the cutting knives thereon respectively and spaced therefrom, each of said combers comprising a substantially circular plate having a central opening therethrough for the respective shaft, substantially the entire periphery of each of said plates lying within the periphery of said cutting knives, said plates each having an extension lying in the same plane thereof and integral therewith, said extensions protruding beyond the periphery of said cutting blades at the top thereof, means engaging said extensions to retain said combers in fixed position, a deflector plate positioned over each series of combers and means to feed material into said cutting knives at the overlapping portion thereof.

2. The combination set forth in claim 1 in which the axes of said parallel rotary shafts both lie in the same horizontal plane.

3. A shredding machine comprising a pair of parallel rotary shafts both lying in the same horizontal plane, a series of spaced circular cutting knives assembled on each of said shafts and rigidly affixed thereon to rotate therewith, the cutting knives on one of said shafts alternating with and overlapping the cutting knives on the other of said shafts, spacers between said cutting knives having contact therewith, a series of stationary combers on each of said shafts between the cutting knives thereon respectively and spaced therefrom, each of said combers comprising a substantially circular plate having a central opening therethrough of greater diameter than that of the spacer and encompassing the latter, substantially the entire periphery of each of said plates lying within the periphery of said cutting knives, said plates each having an extension lying in the plane thereof and integral therewith, said extensions protruding beyond the periphery of the cutting blades at the top thereof, means engaging said extensions to retain said combs in fixed position, a feed hopper having an inlet positioned over the overlapping portion of said cutting knives and an inclined deflector plate posi-

tioned over each series of combers and extending longitudinally of said shafts.

4. A shredding machine comprising a pair of parallel rotary shafts, a series of circular cutting knives assembled on said shafts in alternating and overlapping relationship, spacers between said cutting knives having contact therewith, a series of stationary combers disposed between the cutting knives of one of said shafts, means disposed between the cutting knives of the other of said shafts to expel material from between said cutting knives, said means comprising a plurality of pulleys rigid with said shaft and rotating therewith, said pulleys being positioned between the cutting knives on said shaft, a belt driven by each of said pulleys, means to retain said belts in horizontal position whereby material may be placed on said belts to be fed to said cutting knives and means on said shafts for holding the cutting knives and spacers together.

5. The combination set forth in claim 4 in which bearing means are provided for each of said shafts on each side of the series of cutting knives and spacers thereon and additional bearing means are provided for each of said shafts at one end thereof.
